Fig.3

Fig.4

Fig.5

Fig.6

FIG. 1 is an isometric view of the front and one side of a condensate pump embodying my new design;

FIG. 2 is an isometric view of the rear and of the side opposite that shown in FIG. 1;

FIG. 3 is an elevational view of the side shown in FIG. 2;

FIG. 4 is a bottom plan view;

FIG. 5 is an elevational view of one end thereof; and

FIG. 6 is an elevational view of the end opposite that shown in FIG. 5.

I claim:

The ornamental design for a condensate pump, as shown.
